I. CRANDAL.

Running-Gear.

No 10,360.

Patented Jan. 3, 1854.

UNITED STATES PATENT OFFICE.

ISAAC CRANDAL, OF CHERRY VALLEY, NEW YORK.

RUNNING-GEAR OF WAGONS, &c.

Specification of Letters Patent No. 10,360, dated January 3, 1854.

To all whom it may concern:

Be it known that I, ISAAC CRANDAL, of Cherry Valley, in the county of Otsego and State of New York, have invented a new 5 and useful Improvement in Wagon-Gearing; and I do hereby declare that the following is a full, clear, and exact description of the same, reference being had to the accompanying drawings, forming part of this 10 specification, in which—

Figure 1, is a plan or top view of the wagon, the body being taken off. Fig. 2, is also a top view of the wagon, the front axle-tree and the tongue being turned out of a 15 straight line with the reach, and the top spring reach, which throws them back to their straight or proper position, being shown strained or bent for the purpose of illustrating its application and Fig. 3, is a 20 vertical longitudinal section of the same.

Similar letters of reference in each of the several figures indicate corresponding parts.

The nature of my invention consists in so arranging the connection between the 25 front and hind wheels of wagons that I avoid the practical difficulties of other inventions, viz. by being enabled to use a fixed reach or perch, connected in the usual manner with the hind axle, and by a king or 30 body bolt with the front one. I can draw the wagon without difficulty, over obstructions meeting the rear wheels, without affecting at the same time the front ones. This is effected by means of the spring bar 35 or partial reach placed above the real perch, by which I am enabled to bring back the front wheels into line or track with the hind ones when thrown out, and also by steady- 40 ing the tongue, prevent its swaying from side to side or whipping the horses and thus 45 injuring them. I also by the employment of the additional sway bar *k* in combination with the adjusting spring bar &c., am enabled to keep the front axle true to its set, yet allow the spring bar or partial reach to have its full effect.

This improvement is equally applicable to the ordinary single and double reach wagons at a very slight cost.

50 To enable others skilled in the art to make and use my invention I will proceed to describe its construction and operation.

A A', represent the axles constructed and employed in the ordinary way.

55 B, B', are the front hounds, C' is the

front bolster and C, is the sand board mounted on top of the same. Between the sand board and axle an open space is left for the main reach D', to play freely in as the front axle, &c., are swayed from right to left. The main stiff reach D, extends from one axle to the other and is secured fast in the rear axle A. It is also connected to A', by means of the king bolt F, on which it turns freely as the wagon moves from right to left. By thus having the reach connected directly to the front axle by the king bolt, instead of by a separate pin, the body of the wagon has no strain brought to bear on its four corners when 60 the front axle and tongue are moved to the position shown in Fig. 2.

F, is the upper reach or spring bar which is attached fast to the hind bolster and also to the back hounds at *a*, as seen in Figs. 2 and 3. This reach is made to act as a spring for throwing the tongue from the position shown in Fig. 2, to that shown in Fig. 1, it being made very thin and elastic for a great portion of its length, as seen in Fig. 2.

G, is a slot in the front end of this elastic reach, in which a fixed pin or stop *g*, secured in the bar *h*, plays freely as the carriage changes its position, the reach being kept in contact with the bolt by means of the staple piece *b*, in the manner shown in Figs. 2 and 3, or by a flange on the screw. The object of the slot G, is to allow the front axle to be turned to the position shown in Fig. 2, and thereby avoid too great strain on the spring reach and on other important parts and the advantage of the spring reach is to prevent the tongue injuring the horse when it is in the position shown in Fig. 2, for it will be seen in this view that the spring is strained and expanded and consequently when the horse attempts to move the front axle and tongue to the position shown in Fig. 1 he will be aided by the power of the spring which, as soon as the axle commences to turn in a straight course, will instantly throw the tongue, &c., into their proper positions.

I am aware that John Jones obtained a patent dated Jany. 14, 1851, which by the introduction of a helical spring and slot or sliding bar connecting the hounds or partial reaches (between the front and rear axles) in connection with his perch swiveling on both axles proposes to prevent the effect of whipping the horses with the tongue, and 105 110

drawing it back to the line of travel when moved. I therefore disclaim any part of such devices as he uses; but

What I do claim as my invention and desire to secure by Letters Patent is—

The arrangement of the spring bar (or partial reach) F, furnished with a slot G, the bar h, connecting the sand bar C and upper sway-bar k, in which is inserted the 10 pin g, in combination with the ordinary

reach or perch and running gear of wagons, for the purpose of not only giving direction and steadiness of the tongue under all circumstances, but also preserving the set of the axle at the same time as set forth and 15 shown.

ISAAC CRANDAL.
